UNITED STATES PATENT OFFICE

2,544,066

MECHANICAL CAR WASHER

Richard H. Chenault, Lexington, Ky.

Application December 5, 1947, Serial No. 789,835

5 Claims. (Cl. 15—97)

1

The present invention relates to mechanical car washers and it consists in the combinations, constructions and arrangements of parts herein described and claimed.

It is an object of the present invention to provide a mechanical car washer particularly adapted to the cleaning of automobiles which is wholly mechanical in its action.

A further object of the invention is the provision in a device of this kind of a novel mop construction.

A further object of the invention is the provision of novel means and mechanism whereby an automobile or the like may be quickly washed and mopped by mechanical means.

Other and further objects of the invention will become apparent from a reading of the following specification taken in conjunction with the drawings, in which:

Figure 1 is a plan view of an embodiment of the invention,

Figure 2 is a vertical sectional view taken along line 2—2 of Figure 1,

Figure 3 is an enlarged sectional view taken along line 3—3 of Figure 2,

Figure 4 is a sectional view taken along line 4—4 of Figure 2,

Figure 5 is an enlarged sectional view taken along line 5—5 of Figure 2,

Figure 6 is an elevational view showing certain details of construction, and

Figure 7 is a fragmentary elevational view showing an element of the invention.

Generally, there is provided a car washing and mopping apparatus comprising a suitable compartment into which a vehicle may be driven and provided with an entrance and an exit opening. The compartment is provided with an overhead railway on which is mounted by means of wheels a framework carrying an elongated curtain-like mop on three sides thereof. The framework also carries a plurality of nozzles adjacent the mops and adapted to play upon the outer sides thereof. A flexible hose interconnects the nozzles and a suitable source of water and an electric motor or the like is provided for moving the framework forwardly and rearwardly upon the trackway.

Referring more particularly to the drawings, there is shown therein a compartment having a floor 10 preferably formed of concrete or the like, side walls 11 and 12 and an entrance 13 and an exit 14. The compartment is of generally elongated rectangular shape and is provided with a pair of longitudinally extending rails 15 and 16 adjacent the top thereof.

2

A framework 17 is provided with two wheels 18 at either side thereof which wheels are adapted to run in the trackways 15 and 16 and to support the framework 17. The framework 17 is substantially square in shape and has a pair of longitudinally extending support members 19 each mounted in spaced relation to the sides of the frame.

A curtain-like mop 20 is suspended from each 10 of the members 19, the free ends thereof extending to points adjacent the floor 10. The forward end of the frame has suspended therefrom a curtain-like mop 21.

A plurality of outwardly extending brackets 22 15 affixed to the framework 17 is adapted to hold a U-shaped supply pipe 23 in which is mounted a plurality of spray nozzles 24 which are directed at the mops 20 and 21 and a flexible hose connection 25 interconnects the supply pipe 23 by means 20 of a coupling 26 and a suitable water supply (not shown).

Adjacent either end of the compartment is mounted a transversely extending axle 27 and 28 carrying respectively sprockets 29 and 30 over 25 which sprockets is trained a chain 31, the free ends of which are attached to brackets 32 and 33 carried by the framework 17. The axle 28 is also provided with a sprocket 34 which is interconnected with a sprocket 35 of a motor 36 by means 30 of an endless chain 37. The motor 36 is suitably supported upon a bracket 38 mounted at one end of the compartment.

In operation, it will be seen that an automobile 39 may be driven into the entrance 13 of 35 the compartment and that water may then be supplied to the pipe 23 by means of a suitable valve (not shown) whereby water will begin to play through the nozzles 24 upon all of the mops 20 and 21. The framework 17 may then be reciprocated along the trackways 15 and 16 within 40 the compartment thereby carrying the mops over the automobile 39 to thoroughly cleanse the same, it being understood that the continually renewed water supply passing down the curtain-like mop structures will carry away all dirt loosened by the mops. The action of the motor may be simply controlled either manually or by some suitable automatic reversing mechanism for the motor 36.

While but one form of the invention has been shown and described herein, it will be readily apparent to those skilled in the art that many minor modifications may be made without departing from the spirit of the invention or the 45 scope of the appended claims.

What is claimed is:

1. A mechanical car washer comprising an elongated horizontal compartment having an open end through which a vehicle to be washed can be driven, a trackway mounted on each of the inner side walls of the compartment adjacent the top and longitudinally thereof, a wheeled framework adapted to travel longitudinally in the compartment on said trackways, a plurality of curtain-like mops carried by the framework and depending from each side and at least one end thereof to adjacent the bottom of the compartment, a water supply pipe carried by the framework, and a series of nozzles carried by the pipe and directed at the outer sides of the mops.

2. A mechanical car washer comprising an elongated horizontal compartment having an open end through which a vehicle to be washed can be driven, a trackway mounted on each of the inner side walls of the compartment adjacent the top and longitudinally thereof, a wheeled framework adapted to travel longitudinally in said trackways, a plurality of curtain-like mops carried by the framework and depending from each side and at least one end thereof to adjacent the bottom of the compartment, a water supply pipe carried by the framework, a series of nozzles carried by the pipe and directed at the outer sides of the mops, and means for reciprocating the framework upon the trackway for dragging the mops over the entire body of the vehicle to be washed.

3. A mechanical car washer comprising an elongated horizontal compartment having an open end through which a vehicle to be washed can be driven, a trackway mounted on each of the inner side walls of the compartment adjacent the top and longitudinally thereof, a wheeled framework adapted to travel longitudinally in the compartment on said trackways, a plurality of curtain-like mops carried by the framework and depending from each side and at least one end thereof to adjacent the bottom of the compartment, a water supply pipe carried by the framework, a series of nozzles carried by the pipe and directed at the outer sides of the mops, and means for reciprocating the framework upon the trackways for dragging the mops over the entire body of the vehicle to be washed, said means including a motor and means interconnecting the motor and the framework.

4. A mechanical car washer comprising an elongated horizontal compartment having an open end through which a vehicle to be washed can be driven, a trackway mounted 5

on each of the inner side walls of the compartment adjacent the top and longitudinally thereof, a wheeled framework adapted to travel longitudinally in the compartment on said trackways, a plurality of curtain-like mops carried by the framework and depending from each side and at least one end thereof to adjacent the bottom of the compartment, a water supply pipe carried by the framework, a series of nozzles carried by the pipe and directed at the outer sides of the mops, and means for reciprocating the framework upon the trackways, said means including an axle transversely mounted adjacent each of the upper ends of the compartment, a sprocket affixed to each of the axles, a chain trained over said sprockets and having its ends connected with the framework, a driven sprocket affixed to one of the axles, a suitably mounted electric motor having a drive sprocket and a chain interconnecting the drive and the driven sprockets.

5. A mechanical car washer comprising an elongated washing tunnel into which a vehicle is adapted to be driven to be washed, a mobile carrier mounted for movement longitudinally of the upper portion of the tunnel and above the level of the vehicle, a plurality of curtain-like mops supported by and depending from said carrier to adjacent the bottom of said tunnel and including a mop depending from each side of the carrier for engaging the sides of the vehicle and a mop depending from at least one end of the carrier for movement across the ends, hood and top of the vehicle when said carrier is moved longitudinally of the tunnel and relatively to the vehicle, and a liquid supply means carried by said carrier and including a plurality of spray heads arranged to discharge against the outer sides of said mops.
